J. L. BRILLANTES

ACETYLENE GENERATOR

Filed March 4, 1924

2 Sheets-Sheet 1

This technical drawing illustrates a mechanical apparatus, possibly a press or stamping machine. The drawing is oriented vertically and features a central vertical frame. On the left side, there is a vertical cylinder or piston assembly with a rod extending downwards. The top of the machine is marked with the handwritten text 'Fig. 1.' Above the main frame, there are several labeled parts: '13' on the left, '21' at the top left, '22 25 26' in the upper center, '27' on the right, '28' at the top right, and '29' on the far left. A large, diagonal member labeled '34' and '40' is positioned on the left side. On the right side, there is a vertical pipe or tube labeled '11' and a valve or fitting labeled '12'. The bottom of the frame is labeled with '3' on the left and '8' on the right. The entire drawing is rendered in black and white, with dashed lines indicating hidden or reference features.

UNITED STATES PATENT OFFICE.

JOSE L. BRILLANTES, OF BANGAR, LA UNION, PHILIPPINE ISLANDS.

ACETYLENE GENERATOR.

Application filed March 4, 1924. Serial No. 696,860.

To all whom it may concern:

Be it known that I, José L. BRILLANTES, a citizen of the United States, residing at Bangar, La Union, Philippine Islands, have invented certain new and useful Improvements in Acetylene Generators, of which the following is a specification.

The present invention relates to a carbide gas generating system and has for its principal object to provide in combination a generator of improved structure with a gasometer which will regulate the generator as needed.

An important object of the invention is to provide a device of this nature having a simple and efficient construction, one which is reliable in operation, inexpensive to construct, and well adapted for the purpose for which it is designed.

With the above and numerous other objects in view which will appear as the description progresses, the invention resides in the combination and arrangement of parts and in the novel features of construction as will be hereinafter more fully described and claimed.

In the drawings:

Figure 1 is an elevation of the apparatus embodying my invention;

Figure 2 is a top plan view thereof;

Figure 3 is a detail perspective of the generator showing the parts thereof disassembled,

Figure 4 is a detail section through the lower portion of the generator.

Figure 5 is a perspective view of the bottom of the compartment 3.

Referring to the drawing in detail it will be seen that 1 designates the casing generally which includes the gasometer 2 and the generator compartment 3. The generator 4 is disposed in the generator compartment 3. The gasometer 1 consists of a compartment in which is disposed the bell 5 from which projects an arm 6. A pipe 7 connects the upper portion of the generator compartment 3 with the lower portion of the gasometer 2 and a valve 8 is provided in the bottom end of this pipe for draining water therefrom. A pipe 9 disposed interiorly of the gasometer and communicates with the pipe 7. A pipe 10 is disposed interiorly of the gasometer and communicates with the system line 11. A drain valve 12 is disposed at the bottom end of the pipe 10. Thus the gas generated in the generator com-

partment 3 will be fed through the pipe 7 and collected in the gasometer through the pipe 9 and will be fed from the gasometer through the pipe 10 to the system 11. A 60 valve 40 is located in pipe 7 to be closed when carbide is put in the generator. The generator indicated generally at 4 includes a casing 13, the bottom end of which is tapered as at 14 terminating in the opening 15. A conical-shaped member 16 is positioned immediately above the opening 15 being held in place by the pins 17 or in any other suitable manner. A tube 18 communicates with this conical-shaped member 16 65 and passes vertically and centrally through the casing 13. A shaft 19 is rotatable through the tube 18 and extends through the opening 15 terminating a distance therebelow and having mounted at its lower end a disk 70 20. At the upper end of the shaft 19 which projects above the generator compartment 3 there is disposed a gear 22 which meshes with a spring-actuated gear 23, the spring of which may be wound up by a key 24. A 75 gear 25 meshes with gear 22 and a gear 26 meshes with gear 25. A braking mechanism including a stem 27 cooperates with the gear 26 for holding the actuating mechanism of the shaft 19 in a stopped position. On the 80 stem 27 is provided an engaging member of shoe 28 which is normally held in engagement with the gear 26 by a spring 29. As the bell 5 moves downwardly it will be seen that the arm 6 will engage the top of 85 the stem 27 thus disengaging the shoe 28 from the gear 26 so that the gears 23, 22, 25 and 26 will be free to rotate thereby causing rotation of the shaft 19.

Now the casing 13 is filled with carbide 90 crystals by removal of the cap 30 and these crystals pass by the edge of the cone-shaped member 16 and rest upon the disk 20. They will not, however, normally fall into the water contained in the chamber 3 but upon 100 rotation of the disk 20 by the shaft 19 and its actuating mechanism it will be seen that the crystals will be thrown from the disk into the water. The water line of the compartment 3 is indicated at 33. Water is 105 also provided in the gasometer 2, the water line being shown at approximately 34 so as to seal the gas in the upper portion of the bell 5.

A tube 35 extends downwardly into the 110 compartment 3 along side of the generator in order that crystals may be inserted there-

in which would be too large to go through the generator casing 13 that is which would not pass between the lower edge of the cone-shaped member 16 and the inner surface of the cone-shaped extension 14 and which would not pass through the opening 15. This is used more for emergency purposes or in starting the generation of the gas. The upper end of this tube is closed by a removable cap 36. A cap 37 is provided in the upper end of the compartment 3 in order that water may be inserted therein. Another cap 38 is provided adjacent the bottom of the compartment 3 in order that suitable means may be inserted therein for removing the carbide precipitate.

The bottom of the compartment 3 slants toward the front and a cleaning blade F is movable therealong by means of rod G so that the precipitated carbide may be removed through opening 38.

While the preferred embodiment of my invention has been described in detail, it will be understood that I do not wish to be limited to the particular construction set forth, since various changes in the form, material, proportion and arrangement of parts and in the details of construction may be resorted to without departing from the spirit

or scope of the invention or sacrificing any of its advantages.

What is claimed is:

An acetylene gas generator comprising a generating chamber, a hopper mounted therein and having an inverted frusto conical lower end through which the contents of the hopper are adapted to pass, a tube extending vertically through the hopper, a cone shaped hollow member formed upon one end thereof, a plurality of radially extending pins carried by the lower end of the cone shaped member and resting against the inverted frusto conical lower end of the hopper, a shaft passing vertically through the tube and having its upper end disposed above the hopper and its lower end projecting through the inverted frusto conical end of the hopper, a disc carried thereby upon which the contents of the hopper are adapted to be discharged, means for rotating the shaft at a predetermined time, an element normally rendering such means inoperative and adapted to move to a position to allow such means to operate upon the depletion of the gas.

In testimony whereof I affix my signature.

JOSÉ L. BRILLANTES.
